UNITED STATES PATENT OFFICE.

WILLIAM LITZENBERG, OF MACOMB, ILLINOIS.

IMPROVEMENT IN HORSESHOES.

Specification forming part of Letters Patent No. **57,346**, dated August 21, 1866.

To all whom it may concern:

Be it known that I, WILLIAM LITZENBERG, of Macomb, McDonough county, State of Illinois, have invented a new and useful Improvement in Horseshoes; and I do hereby declare that the following is a full, clear, and exact description thereof, which will enable others skilled in the art to make and use the same, reference being had to the accompanying drawings, forming part of this specification, in which—

Figure 1 is a bottom view of my improved horseshoe, showing a set of winter calks attached. Fig. 2 is a sectional view of the same, taken through the line *x x*, Fig. 1.

Similar letters of reference indicate like parts.

My invention has for its object to furnish an improved horseshoe the calks of which are removable, and the winter-calks both removable and reversible; and it consists of an improved horseshoe formed by combining with the main part of the shoe heel and toe calks, so constructed with double flanges that when one flange has become worn and dull the calks may be reversed and the other flange used, and which may be removed and replaced with new calks without removing the main part of the shoe from the horse's foot.

A is the main part or body of the shoe, which is made of the ordinary shape and attached to the hoof of the horse in the ordinary manner, except that it has one or two holes formed in the middle part or toe of the shoe and one at each end or heel, having screw-threads cut therein for the attachment of the calks. The toe-calk B is formed as shown in Figs. 1 and 2—that is, it is bent up, so that its parts or flanges stand at an angle with each other, as shown in Fig. 2. These parts or flanges are both so formed that either flange may be applied to the shoe, the other flange serving as the calk. One or two holes are formed through each flange of the toe-calks

and one through each flange of the heel-calks C, corresponding with the holes through the main part or body A of the shoe.

The calks B and C are attached to the body A of the shoe by screws passing through the flanges and screwing into the holes formed in the said shoe A, as before described. The calks, when worn or dulled, may be reversed by removing the screws and screwing the other flanges fast to the body of the shoe. The heel-calks C are also made with two parts or flanges set at an angle with each other, as shown in Figs. 1 and 2, and they are reversible in the same manner, except that the calks must be exchanged—that is, the calk C, on one end or heel of the body A, when reversed, must be placed upon the other end or heel of the shoe.

The calks B and C may be reversed or exchanged for new, whenever desired, in a few minutes, without having to take the horse to a blacksmith or to remove the main part A of the shoe from the foot of the horse.

To give additional strength to the attachment of the calks, the toe and heel parts of the body A may be made with a slight projecting flange, as shown in Figs. 2 and 3. This gives a firmer seat to the calks and partly relieves the screws from the strain.

The drawings represent the calks as being held by one screw, and in general this will be found to be sufficient; but in some cases it may be advisable to use more than one screw for this purpose, as before described.

I claim as new and desire to secure by Letters Patent—

Combining with the main part A of the shoe the removable and reversible calks B and C, constructed and applied substantially as herein described, and for the purpose set forth.

WILLIAM LITZENBERG.
